UNITED STATES PATENT OFFICE.

ALFRED JOHN GALLANT, OF SWANNANOA, NORTH CAROLINA.

AUTOMATIC STOP MOTION.

Application filed March 5, 1927. Serial No. 173,079.

The present invention relates to an improved automatic stop motion or mechanism embodying a trip actuated switch control for a machine known to the trade as a napper, but sometimes designated as a raising machine for blankets and flannels.

The purpose of the invention is to provide a dependable stop mechanism for automatically stopping the napping machine when the material is running to the right or the left of its natural course or when two pieces of material are fastened together improperly at a seam, which if run through the machine in this condition, will cause serious damage to the machine.

The improved structure forming this automatic stop mechanism, together with the advantages derived from the special association of parts will become more readily apparent from the following detailed description and the accompanying drawings.

In these drawings:—

Figure 1 is a side view of a napping machine showing the improvement associated therewith and indicating the approximate method of operation.

Fig. 2 is a top plan view of the same.

Fig. 3 is a detail view of one of the end bars of the guide frames showing the switch actuating means.

Fig. 4 is a top plan view of the structure shown in Fig. 3.

Fig. 5 is a view of the opposite end bar of the guide frame showing an adjustable stop device.

Fig. 6 is a top plan view of Fig. 5.

Fig. 7 is an enlarged detail view of one of the material penetrating fingers equipped with a special guide plate.

Fig. 8 is a view of the same structure showing the configuration of the guide plate more plainly.

Fig. 9 is a front elevation of another part of the switch operating means.

Fig. 10 is a side view of the structure shown in Fig. 9.

Fig. 11 is a detail view of one of the intermediate material penetrating fingers.

Fig. 12 is a detail view of one of the intermediate material lifting members over which the material slides freely.

Referring now to the drawings in detail, and especially to Fig. 1, it will be noticed

that the reference character 1 designates generally a conventional form of napper machine such as is employed for treating blankets and flannel in a well known manner. This machine embodies the customary supporting frame and the napper roll 2 driven by means controlled from an electric switch 3. Mounted on this machine as well as on the outwardly extending beams 4 at the top of the machine are guide rollers 5, located at customary suspension points.

The sheets of material to be treated, designated at 6 passes over these rollers in the direction of the arrow. The material is piled on trucks 7, as ordinarily is the case, and passes upwardly over the guide means 8. Under ordinary conditions, two trucks are located beneath this guiding means and the material is piled thereon so that it can be unfolded in the manner indicated. For convenience the piles of material are designated by the reference characters 9.

In this connection, I might direct attention to a receiving truck 10 on which the treated material 11 is piled. It is well to consider the guide means 8 more in detail. In the first place, it is to be stated that this guide means is of conventional construction and comprises depending hangers 12 carrying end bars 13 and 14 between which are the customary transversely disposed guide rods 15.

The foregoing details are old and well known in the art of napping or raising. The improvement comprises first, a rock shaft 16 journaled at its opposite ends in bearings formed in the intermediate portions of the bars 13 and 14. Fastened to the outside of the bar 13, is a stop forming bracket 17 (see Fig. 5), with which an adjustable stop screw 18 cooperates. This screw is carried by a collar 19 which is fastened to the adjacent projecting ends of the rock shaft as indicated plainly in Fig. 6. Mounted on the corresponding portion of the opposite end of this rock shaft is a crank arm 20 (see Fig. 3), which engages a pivotally mounted arm 21.

One end of the arm 21 cooperates with a stop shoulder 22 and a pull wire or rod 23 is connected to the opposite end thereof. By observing Fig. 1, it will be noticed that this rod 23 is adjustable and includes a turn

buckle for this purpose and it extends to and connects with the details shown in Figs. 9 and 10.

Directing attention to these figures, it will be seen that the reference character 24 designates a bracket fastened to the frame of the member adjacent the switch 3. A small shaft 25 is journaled in a bearing on this bracket, and a presser finger 26 is connected 10 with this shaft, and cooperates with a push button on the switch 3.

Also, an additional crank arm 27 connects with this shaft, and with the aforesaid rods 23. A spring 28 connects with the crank arm 15 and with the bracket 24, to normally move the finger 26 away from the switch. Obviously, however, when the rod 23 pulls against the tension of the spring, the shaft 25 is rotated to actuate the finger 26 which 20 in turn operates the switch to open the electric circuit and to stop the machine 1.

In order to produce the foregoing operation, I employ novel material controlled means mounted on the rock shaft 16. To 25 begin with, I employ two duplicate trip and penetrating elements of the construction shown better in Figs. 7 and 8. Each element is longitudinally curved and has a pointed end as indicated at 29 and is provided with a collar 30 fastened to the rock 30 shaft 16 by a set screw. These trips are located near the aforesaid end bars 13 and 14 respectively.

The pointed ends 29 are disposed in a direction opposite to the direction of movement on the moving material, as indicated for instance in Fig. 1. Carried by each element is a guide plate 31, of the configuration shown in Fig. 8. The guide plate is adjustably 40 mounted on the trip by the means 32 as shown. These plates have their curved edges disposed inwardly and arranged in close proximity to the longitudinal edges of the moving material, 6.

45 It is obvious, therefore, that should the material run crooked, the edge will ride up on the curved edge of the plate 31 and at a predetermined time, the points 29 on the trip will penetrate the material and the tendency 50 of the material to move onwardly, will rock the shaft to actuate the switch through the medium of the mechanism described. In addition, to the trips 29, I employ supplemental penetrating elements and trips 33 as 55 shown in Fig. 11. These are arranged on the intermediate portion of the rock shaft. Closely associated with these trips 33, are material lifters 34 (see Fig. 12).

Incidentally, the elements 33 and 34 are 60 arranged in alternate order as represented in the top plan view in Fig. 2, the points on the elements 33 being directed in a direction opposite to the movement of the material, and the hooked upper end 35 of the element 65 34 being directed in an opposite direction,

in order that the material directed thereon may glide very freely over these hooks. The hooks are of a height slightly greater than the elements 33, and it is the purpose of the elements 33 to engage improper seams in 70 the material in order to trip the mechanism and operate the switch.

It will therefore be seen that the machine will be stopped in the event that improper seams occurring in the material or in the 75 event that it moves crooked in the direction from right to left.

Briefly, in the operation the material 6 travels in the direction of the arrows and is trained over the various rollers as shown. 80 Due to improper placement of the trucks 7, the materials usually start to crowd to one side or the other, and move out of a proper course. In case this happens, the longitudinal edge of the material strikes the guide 85 plate 31 and works up on the curved edge thereof until the point 29 on the penetrating trip pierces the material. This causes the rock shaft to oscillate, and to actuate the details 20 and 21 which in turn serve to operate the switch to stop the machine. As 90 before indicated, the object of the intermediate cooperating trips 33 and 34 is to pierce any irregularity or seam in the material and to stop the machine. 95

Of course, the operator has wired the seams together, so that the projecting loose ends are on the wrong side of the material or has left out either one or both seam wires, so that the seam is only half fastened, or 100 not fastened at all. Hence, as the material is drawn across the mechanism, the trips come into play for stopping the machine in order that the error may be corrected.

In connection with the foregoing, it will 105 be noted that the parts 29 and 33 are two very important factors of the structure. The part 34 has a blunt end that points in the same direction that the cloth is moving, and it holds the cloth to keep it from sliding 110 down and engaging the parts 33. The last-named part is provided with a point which catches on an improper seam and trips the mechanism and automatically stops the machine. A seam usually has a two-inch flap 115 on one side.

Naturally when the seam or flap is wrong, it is underneath and hangs down in the path of movement of the part 33. If the seam is proper however, it overlaps or rides on top and no harm can be done. It follows that improper seams providing hanging flaps which trip the parts 33, to automatically stop the machine for the purpose described.

It is believed that by considering the description in connection with the drawings, a clear understanding of the invention will be had by persons skilled in the art to which the invention relates. Therefore, a more lengthy description is thought unnecessary. 130

While the preferred embodiment of the invention has been shown and described, it is to be understood that minor changes coming within the field of invention claimed may 5 be resorted to if desired.

Having thus described my invention, what I claim as new is:—

1. In a structure of the class described, in combination, a napping machine including a 10 support provided with a napper roll, guide rollers, and guide means located in advance of the napper roll, together with an electric control switch, a rock shaft mounted on said guide means, material piercing and trip 15 means carried by said rock shaft said trip means being normally out of contact with the movable material, and engageable with said material when caught by a defective seam, and an operating connection between 20 the rock shaft and switch, whereby when the rock shaft is actuated by the material and trip means, the switch will be turned off to automatically stop the machine.

2. In a structure of the class described, 25 material guiding means for a standard napping machine embodying transverse guide bars and end bars, a rock shaft mounted between the guide bars and in bearings in said 30 end bars, trip mechanism mounted on said rock shaft said mechanism being operable by the action of the traveling cloth, and electric switch operating means associated with 35 one end of the rock shaft, whereby when a defect occurs in the traveling cloth, said trip mechanism will be actuated to in turn 40 operate the switch and stop the machine.

3. In a structure of the class described, 45 material guiding means for a standard napping machine embodying transverse guide bars and end bars, a rock shaft mounted between the guide bars and in bearings in said 50 end bars, trip mechanism mounted on said rock shaft said mechanism being operable

by the action of the traveling cloth, and switch operating means associated with one 45 end of the rock shaft, said switch operating means embodying a crank arm carried by said rock shaft, a pivotally mounted arm with which said crank arm is connected, an adjustable operating rod connected with 50 said pivoted arm, and spring released means associated with said rod and adapted for association with the switch for actuating the switch, whereby when a defect occurs in the traveling cloth, said trip mechanism will 55 be actuated to in turn operate the switch and stop the machine.

4. In a structure of the class described, 60 material guiding means for a standard napping machine embodying transverse guide bars and end bars, a rock shaft mounted between the guide bars and rockable in bearings in said end bars, trip mechanism mounted on 65 said rock shaft, said mechanism being operable by the action of the traveling cloth, 70 switch operating means associated with one end of the rock shaft, said switch operating means embodying a crank arm carried by said rock shaft; a pivotally mounted arm with which said crank arm is connected, an adjustable operating rod connected with 75 said pivoted arm, and spring released means associated with said rod and adapted for association with the switch for actuating the switch with which said rock shaft is equipped, together with guide plates carried by the end trip members, the guide plates 80 having curved edges for cooperation with the longitudinal edges of the moving material, whereby when a defect occurs in the traveling cloth, said trip mechanism will be actuated to in turn operate the switch and stop the machine.

In testimony whereof I affix my signature.

ALFRED JOHN GALLANT.
